UNITED STATES PATENT OFFICE.

WILLIAM GEORGE CLAYTON, OF ST. KILDA, NEAR MELBOURNE, VICTORIA,
AUSTRALIA.

SPARK PLUG.

Application filed July 12, 1926, Serial No. 122,004, and in Australia February 26, 1925.

This invention relates to an improved spark plug and has been devised in order to provide a spark plug of greater utility than those at present in use, the essential features embodied in this invention being as follows:—

1. The arrangement of the electrodes whereby by the operation of the insulation one, two, three or more points may be adjusted to allow of one or more sparks to be operated as required.

2. The insulator is so arranged with positive points that it is interchangeable with any sized plug shell or casing.

3. The use with the features above mentioned of an insulator protruding through the end of the shell with an air space between the insulator and shell for the purpose of allowing the explosive gases entering high up into the plug so that there is no possibility of the spark or sparks taking place in a vacuum and so ensuring that the spark occurs well into the explosive gases, and also allowing of expansion and contraction of the material forming the casing and insulator.

4. The use of a flexible washer or washers to form joints between the insulation and shell and so that when these parts are screwed down there is no possibility of the cracking or breaking of the insulation.

5. A spark plug comprising a metal shell constituting a negative electrode, and insulator in the negative electrode, a positive electrode extending through said insulator and terminating at a point in proximity to said shell and preferably off-set from the centre of the insulator, a plurality of sparking points between the positive electrode and the negative electrode and a portion of said insulator preventing short circuiting between the positive electrode and the nearest portion of the negative electrode and means combining the shell and the insulator whereby the points can be adjusted to allow of a single spark gap or a plurality thereof according to the conditions under which the sparking plug is used, such as a condition necessary to secure a spark of desired intensity.

In order that the invention may be more readily understood it will now be described with reference to the accompanying drawings in which:—

55 Figure 1 is a side elevation.

Figure 2 is a view in plan.

Figure 3 is a view of the underside, and

Figure 4 is a view in section of the improved spark plug.

Figure 5 is a view of the unassembled 60 parts.

According to this invention the preferred construction consists of an insulator 1, the top portion 2 of which is cylindrical and approximately at its centre is formed with 65 an enlarged circular portion 3 to which a flexible metal washer 4 is fitted and from this portion the insulator tapers as at 5 to the lower end preferably a short distance past the bottom of the shell 6.

Passing through this insulator is a positive electrode 7, the top of which is threaded as at 8 to receive a nut 9 for the lead wire 10 of the circuit.

This positive electrode 7 projects through 75 the bottom of the insulator 1 and spaced therefrom are one, two or more sparking points 11 with spark gaps 12 separating the same from the positive electrode 7 and being set into the insulator only as illustrated 80 in Figure 4.

The sparking points 11 and the negative electrode 14 are curved towards each other as illustrated in Figure 4 in order to avoid short circuiting at the base of the insulator 1, the points being directed into the gas space to ensure a more positive spark.

The insulator 1 so constructed is received in an outer shell 6 around its lower portion and this outer shell is threaded at its lower 90 end 13 to be screwed into the cylinder, this lower end being provided with a negative electrode 14 projecting towards the spark gaps 12 in the insulator, an air space 15 being provided between the lower end of 95 the insulator 1 and the shell 6 to perform the functions above described.

In the shell 6 at the point where the lower end of the insulator 1 tapers downwardly is a conical flexible washer 4 conforming substantially to the shape of that portion of the insulator 1 and which imparts a certain amount of resiliency to prevent the breaking or cracking of the insulator 1 when the parts are locked together by a locking nut 16 100 screwing into the casing or shell 6 at the top and around the insulator 1.

By arranging the parts in this way the insulator 1 and shell 6 are interchangeable, the spark gaps can be adjusted so that one 110

or more are given according to such adjustment and the lock nut 16 also bears on a flexible metal washer 4 which allows the combining of the parts together without the 5 fear of breaking the insulator.

The insulator can be constructed of any suitable non-conductive material such as porcelain, mica, lava or any other suitable material and I desire it to be understood 10 that various improvements and modifications may be embodied without departing from the spirit and scope of the invention.

What I claim as my invention and desire to secure by Letters Patent is:—

15 In a spark plug, a grounded electrode, an insulator, and a plurality of electrodes car-

ried by said insulator the sparking points of which are arranged in chords of arcs of a circle concentric to the axis of said insulator, the circumference of which circle lies 20 within sparking distance on said grounded electrode, said plurality of electrodes forming a series of spark gaps, and said insulator being adjustable by rotation so as to bring the terminal electrodes of any of said chords 25 into sparking relation with said grounded electrode for the selective production of different numbers of sparks, in series.

Signed at Melbourne, Victoria, Australia, this 1st day of June, 1926.

WILLIAM GEORGE CLAYTON.
